UNITED STATES PATENT OFFICE.

WILLIAM E. NEAL, OF ST. PAUL, MINNESOTA, ASSIGNOR TO BROWN & BIGELOW, OF ST. PAUL, MINNESOTA, A CORPORATION OF MINNESOTA.

READY-REFERENCE CALENDAR.

1,268,599.

Specification of Letters Patent.

Patented June 4, 1918.

Application filed May 25, 1914. Serial No. 840,738.

To all whom it may concern:

Be it known that I, WILLIAM EDWARD NEAL, a citizen of the United States, and a resident of the city of St. Paul, in the county of Dakota, State of Minnesota, have invented certain new and useful Improvements in Ready-Reference Calendars, of which the following is a specification.

My invention relates broadly to calendars and more particularly to a combined wall calendar and reference calendar.

The principal object of this invention is to provide a reference calendar wherein the cover thereof comprises a backing for a wall calendar of the usual type.

A further object of my invention is to provide a wall calendar whereon definite dates may be indicated and thereby refer to memoranda concealed within the reference calendar constituting the back for the wall calendar.

A still further object of my invention is to provide a wall calendar upon the cover for a memorandum calendar and fasten the leaves of the memorandum calendar together by means of the cord for suspending the wall calendar.

Other and further objects of my invention will in part be obvious and will in part be pointed out in the specification hereinafter following by reference to the accompanying drawings wherein like characters are used to represent like parts throughout the several views thereof.

Referring specifically to the drawings—

Figure 1 is a perspective view showing the device hanging on a wall as an ordinary calendar, thereby concealing the memorandum calendar. Fig. 2 is a view showing the calendar open in such manner as to expose both the calendar pad and the memorandum calendar. Fig. 3 is a modified form wherein one back of the memorandum calendar is extended longer than the other and the wall calendar pad is mounted upon the face of the longer back.

Heretofore memorandum calendars were usually formed with open leaves whereon the memoranda might be arranged and were thereby open so that anyone noticing the date might also read the memorandum. Such calendars did not facilitate the making of private memoranda which it was desired the general public might not see.

My invention provides an ordinary calendar on which definite dates may be specifically designated and the particular event to occur on that date may be indicated on the memorandum calendar within the backing for the wall calendar pad and thereby effectively concealing the memoranda and at the same time calling the attention of the user of the calendar to the definite date.

Referring particularly to the drawings, the mount for the wall calendar pad 1, which may be of the usual form having one leaf for each month, comprises a memorandum calendar back or book. The calendar pad 1 may be mounted on the outer cover 2 of the book, and preferably the calendar pad, is mounted in such manner that the length of the pad corresponds with the length of the back, as is shown in Fig. 1. The back of the memorandum calendar book may be perforated as at 4 and a securing and supporting cord 5 may be passed through said perforations. This cord may be used to perform the double function of securing together the leaves 6 of the memorandum calendar book and for supporting the device for use as an ordinary wall calendar, by looping the cord 5 over a support such as the nail 7, as shown in Fig. 1.

The memorandum calendar 8 is provided upon the leaves 6, and preferably is arranged as shown in Fig. 2, wherein a portion of the leaf comprises a memorandum calendar having a line 9 for each day of the month arranged to cover a portion of a page, and the remaining portion of the page, such as 10, may be utilized for printing or writing thereon, information, advertising, etc.

The device disclosed in Fig. 3 is similar in character to the device disclosed in Figs. 1 and 2 with the exception that the back cover page 11 is arranged larger than the front cover page 12 and the calendar pad 1 is mounted upon the inner face of the back cover page in such manner that when the back cover is folded as shown in Fig. 3, the calendar pad is concealed. The memorandum calendar and other portions of the device are identical with that disclosed in Figs. 1 and 2.

The use of the memorandum calendar may be illustrated by designating the date "June 30th" by means of an "X" as shown in Fig. 1. This designation indicates to the

user of the calendar that his attention is called to the true memorandum calendar. Upon opening the memorandum calendar to the month of "June" and upon referring 5 to the "30th" he finds a memorandum notation, such as for example "Note due".

It will be seen that when the calendar is in use as an ordinary wall calendar as shown in Fig. 1, there is no indication visible other 10 than the "X" mark, and it is necessary to remove the calendar from the nail and open it to the memorandum calendar to ascertain to what the notation refers.

Having thus described my invention what 15 I desire to claim is:

1. A device of the character described, comprising a book, a memorandum calendar within said book, said memorandum calendar comprising designations for the days 20 of the month, lines adjacent said designations to provide suitable writing spaces

adjacent the said designations for the purpose of receiving memorandum notes, a back-
ing covering and concealing the memoran-
dum calendar, means to suspend said book
with the back thereof upward and the free
edges downward, and a calendar pad mounted
upon the said cover and normally not
concealed, said calendar pad being provided
with designations for the days of the week. 25

2. As an article of manufacture, a booklet, a memorandum calendar within said booklet, a cover for said booklet, means to suspend said booklet to normally conceal the memorandum calendar, and a normally ex-
posed calendar mounted upon the cover and
arranged to be readable when said booklet
is suspended. 30

WILLIAM E. NEAL.
